UNITED STATES PATENT OFFICE

ALBERT J. LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF DELAWARE

LINK

Application filed January 2, 1929. Serial No. 329,817.

This invention relates to improvements in links. More especially it has to do with thermally responsive links which upon rise of temperature to a predetermined degree give way and thereby free whatever has been held in restraint by them.

So far as I am aware all such links heretofore used have employed some kind of fusible material which becomes more or less plastic at relatively high temperatures. Because of the tendency of such material to yield gradually at normal temperatures it has become customary to interlock the separable parts of the link so that these parts themselves will carry the major portion of the load while the fusible material is maintaining this interlocked relation. By thus lessening the amount of strain on the material the trouble from "cold flow" is largely avoided but the arrangement is not entirely satisfactory because the fusible material is usually more or less insulated as it were by the interlocked parts and does not respond as quickly to changes of temperature.

Moreover all fusible material is subject to corrosion. In some cases this eats away the fusible material and permits a premature rupture of the link with possible damaging results if the link has been holding a fire extinguishing agent in restraint. Far greater difficulties are encountered, however, in the cases where the effect of the corrosion is to change the molecular structure of the fusible metal as for example where it forms a sulphide of the metal. This action is not apparent because the external appearance of the material is unchanged, but its effects are exceedingly dangerous because the resulting material has greater holding power and is less responsive to heat changes. In extreme cases the material in fact becomes non-fusible. Accordingly, it is not uncommon to find fusible links so corroded as to be entirely inoperative in respect to the functions they are expected to perform. This is obviously a dangerous possibility and one likely to be unnoticed because, as previously stated, the effects of the corrosion can not be seen and the actual condition of the fusible material can not be determined by visual inspection.

Moreover, most links are installed and soon forgotten because they maintain something, a closure for example, in its normal and usual position and so long as this position continues there is nothing to call particular attention to it and to its restraining means.

So it is desirable to have a link which will be entirely free from the danger of corrosion, which will not be in any way impaired by being exposed for long periods to normal temperatures, which will not require supervision or maintenance, which will respond unfailingly when needed, and which has as its yielding element one which is capable of bearing the full force exerted upon the link. It is to the provision of such a link that the present invention is directed.

A principal object of this invention is to provide a simple link comprising only separable members which are engaged by the ties and an element holding said members against separation. It is a feature of the invention that this element bears all the load imposed on the link, is noncorrodible, and becomes entirely destroyed when heated to a predetermined temperature, thus completely severing all connection between the ties. As herein illustrated, the thermally responsive element is a frangible vessel preferably made of quartz and containing a charge of expandible fluid which upon being heated to a predetermined degree completely destroys the vessel. The latter may be made from tubing with its end portions formed generally in spherical shape, each end being joined to the main body portion of the vessel by a neck portion of somewhat smaller dimension. The end members of the link engage only the spherical ends of the frangible vessel so that the force transmitted by them is entirely carried by the vessel. Upon the rupture or destruction of the vessel the link ends are instantly and completely set free with no chance of their becoming entangled or interlocked with one another.

It is intended that the patent shall cover by suitable expression in the appended claims whatever features of patentable novelty exist in the invention disclosed.

In the accompanying drawings,

Figure 1 is an elevation partly in section of a thermally responsive link constructed in accordance with the principles of the invention.

Figure 2 is a similar view of the same link viewed as from the left of Figure 1;

Figures 3 and 4 are similar views showing a modified form of link ends; and

10 Figure 5 is a view showing the link end of Figures 3 and 4 as it may be stamped from sheet stock.

Referring particularly to the drawings, the link of Figures 1 and 2 has end members A formed with a flat portion A1 and a hollow cylindrical portion A2 in alignment with the flat portion. Each end portion has a hole edged with a grommet B through which ties may be secured to the link. A spherical or ball-shaped end C1 of a frangible vessel C is inserted within the hollow of the cylindrical portion of each end member, the rim A3 of the cylinder being then turned or spun inward to fit somewhat loosely about the neck C2 of the vessel.

Thus the separable end members of the link are joined to the vessel. The latter is preferably made of quartz initially formed as a tube and then fused and drawn into a vessel of the shape disclosed, with its ends generally spherical and joined to the body portion C3 by the contracted neck portions C2. Before being entirely sealed the vessel is charged with a fluid that expands upon being heated.

The relation of the expansive force of this fluid to the temperature is such that the degree at which the vessel will fail to withstand its internal pressure can be predetermined with considerable accuracy. Consequently a link employing the frangible vessel as its thermally responsive element can be depended upon to withstand without change the effects of all normal temperature and to be completely destroyed when exposed to a temperature at which the expansive force of the fluid overcomes the strength of the quartz shell. The latter, of course, is non-corrosive and by selecting suitable metal for the link ends the danger from corrosion is substantially eliminated.

50 The link of Figures 3 and 4 has end members D which can be stamped from sheet stock in the form of a strip with a hole D1 at one end and slot D2 extending from a similar hole D3 at the other end slightly more than half the length of the strip. The hole D3 is larger than the diameter of the ball-shaped end C1 of the frangible vessel so that the latter can be inserted therethrough and its neck portion C2 slipped along the slot D2.

60 The strip is then bent around to form a ring D4 with portions D5 off-set therefrom which are clamped together by the grommet B. Thus the ball-end of the vessel is held within the ring of the end member.

65 Ties (not shown) are attached to the sep-

arable end members through the grommets B and the entire load carried by these ties is transmitted to the frangible vessel. When the latter is demolished by the expansive force of its fluid charge the link as such is 70 completely destroyed and the ties entirely set free.

The universal-joint type of connection between the end members and the frangible vessel permits limited relative movement between them so that they will position themselves in alignment although there may be an angular divergence between the planes of the grommets B. The term "tie" as used in the claims is not to be limited to a flexible 75 band or fastening, but is to be taken as representative of any force-exerting agency capable of being attached to the end members.

I claim as my invention:

1. A thermally responsive link comprising, 85 in combination, separable means adapted to be connected to ties and a frangible vessel holding said separable means from separating and containing an expansible fluid adapted upon rise of temperature to a predetermined degree to destroy said vessel and thereby free said separable means; the said means being connected to the ends of said frangible vessel to permit limited relative movement between them. 90

2. A thermally responsive link comprising, 95 in combination, a frangible vessel containing a charge of expansible fluid adapted upon being heated to a predetermined degree to destroy said vessel; and separable members adapted to be connected to ties and engaging said vessel near its ends with freedom for limited relative movement between them; said engagement holding said members from separating until the destruction of the frangible vessel. 100

3. A thermally responsive link comprising, 110 in combination, a frangible vessel containing a charge of expansible fluid adapted upon being heated to a predetermined degree to destroy said vessel; and separable members adapted to be connected to ties, each member having a ring-shaped portion engaging the surface of said frangible vessel in a manner to permit limited relative movement between 115 them while preventing separation of said members prior to the destruction of the said vessel.

Signed at Providence, Rhode Island, this 28th day of December, 1928.

ALBERT J. LOEPSINGER.
